UNITED STATES PATENT OFFICE.

TALBOT C. DEXTER, OF PEARL RIVER, NEW YORK.

PAPER-CUTTING MACHINE.

Application filed August 27, 1925. Serial No. 52,741.

This invention relates to paper-cutting machines of the guillotine type and particularly to a heavy duty power driven machine.

5 Among the objects of my invention is to provide a machine in which the descent of the paper clamping means is controlled by the power drive means of the machine and is so timed that the clamp will descend 10 ahead of the knife so that the pile of paper will be clamped soon after the machine is started and then given an additional clamping pressure before the cutting edge of the knife comes into contact with the surface of 15 the top sheet of paper in the pile.

Another object of my invention is to provide a one-piece clamp which may be lowered and pressed upon a pile of paper as the result of an operation of a treadle and to 20 provide restoring means capable of returning the clamp to its raised position upon an easing off of pressure or change of position of the treadle.

Another object is to adapt a one-piece 25 clamp, which has a treadle related thereto for the purpose of preliminarily lowering the clamp to gauge the work independent of any power actuation, to be operable during a cutting cycle of operation of a paper cutting machine to descend to the surface of the 30 pile of paper in advance of the knife, and to be securely pressed against the pile of paper during the contact of the knife with the paper.

35 Another object is to provide mechanism for lowering the clamp and applying pressure thereto in the lowered position by power and independent of the actuation of the knife.

40 Another object is to provide mechanism which delays in lifting the clamp until after the knife has started its upward motion and has withdrawn from contacting relation with the pile of paper.

45 Another object resides in providing mechanism which is adjustable to cause any definite amount of pressure desired to be applied to the clamp after it has descended onto the pile of paper.

50 Another object resides in producing an operation controlling mechanism which re-

quires a plurality of movements by the operative before the machine is connected to the source of power and which will be returned to its normal position when the machine is automatically stopped at the end of a cycle.

Another object is to provide operations controlling devices which are under the control of an operative to release shaft locking 60 devices and thereafter cause the machine to be driven by power, said operations controlling device being automatically operated at the conclusion of a cycle of operation of the machine to disconnect the machine from its 65 source of power, stop the machine with the knife in an elevated position, restore an operative's control lever to normal position, and lock the shafts from further operation thereby requiring another manipulative effort 70 by the operative before the machine can be operated or the knife can descend.

Another object is to provide safety devices which are controlled by the operation controlling mechanisms for locking the 75 knife in its raised position and releasing it when the machine is to be operated.

With these and incidental objects in view the invention consists of certain novel features of construction and combination of 80 parts, the essential elements of which are set forth in the appended claims and in preferred embodiments which are hereinafter described with reference to the drawings, in which

Fig. 17 is a sectional view of a modified form of mechanism for applying pressure to the clamp independent of the operation of the machine, and is taken on line 19—19 of Fig. 21.

Fig. 18 is a view of the same mechanism 25 with the clamp under pressure.

Fig. 19 illustrates the position of the various parts of the clamping mechanism after pressure has been released.

Fig. 20 is a front elevation of this modified form with parts broken away and in section.

Fig. 21 is a plan view of the modified form with the table, clamps, and knife stock removed and the side frames in section. This view also shows a modified form of operation starting lever which may be used.

Fig. 22 is a detail of the modified form of operation starting lever in its unlatched position.

Fig. 23 illustrates the second position with the machine unlocked.

Fig. 24 illustrates the third position when the machine is clutched for operation.

Fig. 25 is another view of the modified form of controlling and locking mechanism.

The frame of the machine consists of two side pieces 1, 2, held together at their bottoms by three rods 3, and at their tops by a channel casting 4. The knife stock 5 moves in a diagonal direction between front and rear guides 6, 7, fastened to each side piece of the machine above the bed or table 8 and is provided at its ends with horizontal slots 9 for engagement with the rollers 10 carried by straps 11, by which the stock is actuated. The straps consist of integral castings and move vertically in guides 12, Fig. 2, and are reciprocated to elevate and depress the knife stock by means of connecting rods 13 adjustably connected to straps 11 and to cranks 14 on the end of the transverse shaft 15 near the bottom of the machine. For the purpose of adjustment, the connecting rods 13 are subject to be lengthened or shortened by a threaded portion 16,

and bolts 17 are provided at the top of each strap for further adjustment. Each of the straps is kept from lateral displacement by a pair of clips 18.

The shaft 15 is driven in a counterclockwise direction (Fig. 2) by means of power derived from the continuously rotating shaft 19 at the rear of the machine which is driven by any suitable means. In the accompanying illustration, a belt is shown driving through a fly-wheel 20, and near the center of the shaft there is slidably mounted thereon the inner member of a friction cone clutch. The outer member 20 of the cone clutch is secured to sleeve 21 which is loosely journaled on shaft 19 and it has fastened thereon a drive pinion 22 which drives gear 23 on shaft 24. Shaft 24 carries pinion 25 which meshes with gear 26 on the knife actuating shaft 15.

The engagement of the cone clutch surfaces for starting the operation of the machine is achieved by the manipulation of an operative's handle 27 conveniently located at the right side of the machine. To cause the clutch to engage, lever 28 must be swung from right to left around stub shaft 29 but in order to prevent inadvertent movement or careless manipulation, a tongue (Fig. 1) is provided on the end of the lever which engages in a hole in the stub shaft when the lever is in its normal position.

The tongue is raised out of the hole by a slight clockwise rotation of lever rod 28 which causes the saw-edged collar 30 fast thereto to displace the lever rod axially. When the operating lever rod is rocked, it swings crank arm 31 which in turn rocks crank arm 32 by means of link 33. Crank arm 32 is fast to shaft 34, Figs. 1, 3, 4 and 5, the clockwise rotation of which, as seen in Fig. 1, moves slidable shaft 35 to the right by means of a yoke formed by two arms 36, 36 which engage a pin that passes through a collar 37 on shaft 35. This slidable shaft carries a brake block 38 having two edges 39 for coacting with rollers 40, one at each end of an exterior brake-band 41. This brake-band is mounted on the outer surface of the outer or driven friction cone 20 and it consists of two bands which are pinned together at the bottom. This pin, 42, passes through ears 43 in a small casting 44 which is fastened to a bar 45 for holding the band from rotary displacement.

A pin or bolt 46 passes through the upper end of the bands and a spring 47 thereon is compressed by a handwheel 48 depending upon the braking effect desired. This bolt is held from rotary displacement by an arm 49 extending from a frame piece. As the brake block is moved to the right, the brake band is immediately expanded by the wedging effect on the rollers and the outer friction cone is released.

The inner friction cone is forced into the

outer friction cone by means of a set of toggle links 50, which are pivoted to a collar 51 securely mounted on shaft 19.

Force is applied to the toggle links through the interposition of a collar 52 slidably mounted and keyed to the same shaft. A yoke 53 extends from shaft 35 and engages collar 52 so as to move it with shaft 35 to straighten or open the toggle links and cause

engagement or disengagement of the clutch members. Thus a right hand movement of sliding shaft 35 causes sleeve 21 to be driven through the cone clutch by the continuously rotating power shaft 19.

It is important that the knife be stopped in its upper position at the end of every cutting stroke, and to do this with the certainty necessary requires that the clutch be released and the brake be applied automatically and with a precision that will insure a stoppage of the travel of the knife at the exact position desired. When the machine is started, shaft 34 is rocked clockwise, Fig. 1, and arm 54 raises loop 55 by means of links 56. There is securely fastened to shaft 15 a disk 57 (Figs. 1, 6 and 7) which carries a cam finger 58 pivoted thereto and set into a sector 59 cut into the disk so as to limit its arc of swing. Just before the end of a revolution of shaft 15, cam finger 58 strikes roller 60 on loop 55 and the finger is pivoted rearwardly against the effect of spring 61 until it bears against abutment 62 (Fig. 6). The continued motion of the disk causes the cam finger to force the roller 60 and loop 55 down and thus cause a sudden counter-clockwise movement of shaft 34 which kicks shaft 35 to the left, breaking the cone friction clutch drive connection and causing the brake band to seize the outer surface of the outer cone of the clutch by the withdrawal of wedges 39 already described. By careful adjustment, whatever desired position of stoppage of the knife may be obtained. Spring 61 is provided to push finger 58 forwardly to the position shown in Fig. 7, after it has functioned to depress loop 55 so that the loop may be raised for the next operation without interference.

When the knife is in its raised position, it is desirable to lock it there as a safety precaution and the locking means are under the control of shaft 34. Fastened to the rear of the right hand knife stock strap 11 is a piston rod 63 which carries at its lower end a piston head which travels in a cylinder 64 having an opening at the bottom to allow oil to be drawn in or out, depending upon the direction of movement of the piston. When the knife is rising, the piston draws oil from a reservoir 65; and when the knife has reached its upper limit, a valve 66 is closed by means of the movement conveyed through link 67 and one arm of yoke 36 (Fig. 3) on shaft 34 by the sudden down-

ward movement of loop 55, thereby preventing the discharge of oil from the cylinder and a consequent drop of the knife. When shaft 34 is rocked clockwise (Fig. 1) in starting the machine, the valve will be immediately opened and the knife then can be drawn downward and the oil from the cylinder will be displaced by the piston and forced into reservoir 65.

Two-piece clamp.

In one modification of my machine the paper to be cut may be held in place before the application of the full clamping pressure by a foot operated clamp. The means for preliminary clamping comprises a lower clamp 70 connected at its ends to a pair of vertical slides 71, Figs. 3, 4 and 5. The lower ends of these slides each have a pin 72 adapted to fit into an elongated recess at the extremity of each arm 73 fastened to shaft 74. Shaft 74 has at its center a crank arm 75 at the end of which is connected a link 76 pivoted at its lower end to treadle 77, the rear end of which is rotatively mounted on the middle tie-rod 3.

Springs 78 are stretched between arms 73 and slides 71 so as to keep the arms elevated and create a lost motion between them and the slides when the foot is first applied to the treadle.

At the top, each slide 71 is equipped with a stud 79 extending laterally therefrom and carrying a socket 80 for the retention of a rod 81. This rod slides through a block 82 and is encircled by a helical spring 83 the lower end of which bears in a recess in the block. It will therefore be seen that the compression in the spring normally holds the lower clamp in an elevated position against the upper clamp 84.

After the paper is initially clamped, upper clamp 84 is allowed to be depressed by power means subsequently to be described and comes quickly into contact with the lower clamp which is bearing against the pile of paper, and before the knife reaches the top of the pile of paper, a final application of pressure is made. It is evident that both clamp 70 and clamp 84 may be depressed simultaneously through the operation of upper clamp 84.

Upper clamp 84 consists of a channel-shaped casting and is fastened at its ends to slides 85 which are guided to slide in a vertical direction by grooves in side frames 1 and 2, and are themselves designed to form the guiding means for slides 71. To each of the lower ends of slides 85 is secured a block 82 having a rack engaging a sector 86 keyed to shaft 87. Power is applied to the clamp through this shaft by means of the mechanism about to be described.

Just to the right of the center of shaft 87 (Fig. 5) there are mounted two collars 88

and 89 each having respectively a lug 90 and 91. Collar 89 is pinned to shaft 87 and in a normal position, Fig. 8, lugs 90 and 91 are in contact. Collar 88 carries an arm 92 to the end of which is pivoted a link 93. Loosely pivoted at its rear end on sleeve 94 is an arm 95 which carries a planetary gear 96 that meshes with gear 97 fast to sleeve 94. The planetary gear has a crank pin connection with the lower end of link 93. Sleeve 94 is driven in a clockwise direction, Fig. 8, by gear 98 which is driven through idler pinion 99 by gear 100 on shaft 15. Planetary gear 96 will rotate counterclockwise, thus creating a pull on link 93 and a tendency to cause the planetary gear to travel counterclockwise about shaft 24. Arm 95 has at its forward end a roller 101 which, in the normal position, rests against the top of cam 102 secured to shaft 15 and prevents arm 95 and planetary gear 96 from dropping. The first few degrees of rotation of shaft 15 removes cam 102 from under roller 101 and crank arm 92 is suddenly pulled down due to the combined effect of the planetary and rotary movement of planetary gear 96. This sudden rotation of collar 88 breaks the contact between lugs 90 and 91 and the restraining force of the upper clamp is withdrawn, with the result that both upper and lower clamps descend to the surface of the pile of paper as shown in Fig. 9 immediately after the machine is started. It is apparent from Fig. 9 that the paper is securely clamped before the knife has traveled but a short distance from its raised position.

Application of pressure by power.

It is also desired that the paper be firmly compressed to a desired maximum pressure before the knife starts to cut and in order to accomplish this I provide a slip clutch through which power is applied to the clamp to its maximum amount before the knife 40 comes into contact with the pile of paper. Referring particularly to Figs. 13, 14, 15 and 16, to shaft 87 there is keyed to turn therewith a sleeve 103 carrying a set of friction plates. Freely mounted on this sleeve is a housing 104 to which is fastened other friction plates, the housing being covered by a cover plate 105 fastened thereto by means of screws. A follower plate 106 is loosely mounted on an end of sleeve 103 and is slidably along the axis of the sleeve for the purpose of adjusting the pressure between the friction surfaces. Intermediate plate 108 and cover plate 105 are a set of compression springs 107 for maintaining an initial pressure and a set of levers 108 having rollers 109 are provided for squeezing the friction plates together. Force is applied to the levers through a threaded collar 110 and when the desired pressure is obtained, lock nut 111 is tightened into place against the

hub of cover plate 105. A graduated scale 112 is provided to indicate the position of set. When the clamps descend, shaft 87 will be rotated through the medium of sectors 86 and owing to the keyed connection of sleeve 70 103 and friction disks, housing 104 and all of its contents will rotate therewith.

It is obvious from the foregoing that the shaft may be rotated by a torque applied to the housing and this manner of rotating 75 shaft 87 is employed when the final clamping force is applied to the pile of paper prior to the cutting operation. The slipping of the friction plates allows for measurement of the amount of pressure desired. Fastened to the 80 left face of housing 104 is a ring 113 having saw teeth for rotating the housing counterclockwise, Fig. 14. Loosely journaled on the hub of the housing is a spider 114 which has three arms at the extremities of each of 85 which is journaled a ratchet 115 continuously urged in the direction of the saw toothed ring by means of spring 116. To control the engagement of these ratchets, each ratchet has secured to the other end of 90 its shaft a small crank 117 from which protrudes a crank pin 118 the extremity of which is engaged in a slot in an arm of spider 119 loosely mounted on a hub of spider 114. Force is communicated to spider 95 114 from shaft 15 by means of eccentric strap 120, Figs. 5 and 8, through arm 121, pin 122, and slot 123. Slot 123 is elongated to provide for lost motion so that when the eccentric starts to move rearwardly from its 100 normal position, Fig. 15, it will first rock spider 119 and thereby release ratchets 115 for engagement, Fig. 16.

Continued rearward motion of arm 121 would cause housing 104 to be driven by 105 spider 114 if it were not for the fact that the housing is rotating at a faster rate due to its frictional relation with shaft 87 which is at this early part of the cycle being rapidly rotated by the falling clamp by reason of 110 the quick release thereof by the planetary gear system previously described. Consequently, the slower movement of drive spider 114 will cause the ratchets to be relatively held to ride over the teeth until the downward progress of the clamps is arrested by the pile of paper as shown in Fig. 9. At this point, housing 104 momentarily stops and the drive spider and its pawls are now effective to drive it further. This driving effect 115 comes through the eccentric strap and the maximum pressure exerted on the paper is dependent on the torque required to overcome the frictional contact of the plates in the slip clutch. This maximum pressure is 120 maintained through the cutting operation, Figs. 10 and 11, by the slipping of the friction plates. This operation may include the upstroke as well as the downstroke of the 125 knife, for it is advantageous to maintain the

paper compressed as long as the knife is in contact therewith, so as not to cause irregularities in cut or tearing of edges. It will be readily understood that the period of the force application to the clamp with respect to the position of the knife is dependent upon the angular position that the eccentric bears to shaft 15.

Preferably after the knife has started its upward stroke, the eccentric has started its forward movement of arm 121 and pin 122 is drawn to the front edge of elongated hole 123 thus rocking spider 119 clockwise and disengaging ratchets 115 as seen in Fig. 12, and spider 114 is thereafter returned by the eccentric to the position shown in Fig. 8. It is held in this position by a rod 124 fastened thereto and having a frictional contact with a roughed surface 125. The upper end of slot 126 in the rod bears against pin 127 and holds the spider in the position shown in Fig. 8 when the machine is at rest, so that the ratchets will remain disengaged.

Meanwhile, as the knife is rising, collar 89 is being rotated clockwise on shaft 87 by the planetary gear system, and its lug 90 is approaching lug 91 of fixed collar 89 which is still displaced from its normal position because the clamps have not as yet been raised, Fig. 12, except for a small distance which is effected by the natural expansion of the pile of paper when the mechanical pressure is relieved. However, preferably when the knife is away from the pile of paper, the front face of lug 90 contacts the rear face of lug 91 and rotates shaft 87 so as to raise the clamps. This movement is rapid and occurs during the last part of the cycle of operation when cam 102 raises arm 95 and the upward motion of link 93 is accelerated thereby.

When the automatic throw-out mechanism operates, all of the parts are left in the position shown in Fig. 8, with the exception that the housing of the friction clutch has been displaced slightly in a counterclockwise direction.

One-piece clamp.

While the mechanisms hereinbefore described are admirably adapted to produce a complete clamping pressure a considerable period of time before the descending knife strikes the surface sheet of the pile of paper, and also to maintain pressure upon the paper until the knife is being withdrawn. I have devised other mechanisms by which the same results may be obtained and which will now be fully described. In Figs. 17, 18, 19, 20 and 21, I have illustrated a one-piece clamping bar which may be fully depressed onto the pile of paper before the operative throws over the control lever to clutch in the knife operating shaft.

This preliminary clamping operation is

controlled by a treadle and is independent of the paper cutting operation. The operation of the treadle causes a toggle to be opened to allow the clamp to descend. When the operating lever is thrown, the power for actuating the knife is thrown in and additional pressure is applied to the clamp before the knife strikes the paper. The knife is withdrawn from the pile of paper before the additional pressure is relaxed.

This clamp also has the advantage of being a one-piece clamp capable of being automatically actuated without the use of a foot treadle, and so timed in its pressure rendering effort as to maintain the pile of papers compressed while the knife is passing through it in either the cutting or withdrawing stroke.

The mechanism about to be described may be assembled in a machine similar to that described except for the replacement of the mechanism for operating the two-piece clamps for the mechanism necessary to operate the one-piece clamp, and the same numerals will be used to designate similar shafts.

One clamping bar 129 serves for all of the purposes of the two clamps formerly described, and it is fastened at each end to a slide 130 which carries at its top abutment 131 and at its lower end block 132 each block having a rack for engaging a sector 133 secured to shaft 87. The clamp is held in its raised position by toggle links 134 the lower one of which is pivoted to the side of planetary gear 134' supported on a triangular lever plate 135 journaled to swing about shaft 24. The upper end of the toggle is pivotally connected with crank 136 on collar 137 loosely mounted on shaft 87. Collar 137 has a lug 138 which contacts lug 139 of collar 140 fixed to shaft 87 when toggle links 134 are straight, thereby maintaining clamps 129 raised, Fig. 17.

Lowering of clamp to gauge work.

To cause the clamp to fall for the purpose of gauging the work, treadle 141 is depressed and link 142 pinned to its rear end is raised and causes lever 143 to be swung clockwise about shaft 19 as a pivot, thereby engaging the leather-covered friction roller 144 with the high surface 145 of disk 146 on shaft 147. This disk is thereby connected to the continuously rotating power shaft 19 through gears 148, and gear 149 which has mounted on its hub friction roller 144. Pivotally connected to disk 146 is a link 150 which is connected by a pin to crank 151 fixed to shaft 152. Shaft 152 has fixed to its ends collars 153 having fingers 154 for contacting fingers 155 on cranks 156 which have connecting rod connections 157 with blocks 132.

When the treadle is depressed, link 150

starts to move forwardly due to the friction contact 144-145, fingers 154 are swung counterclockwise, Fig. 17, and just before they strike fingers 155, crank 158 which is 5 also fastened to shaft 152 exerts a pull, through rod 159, on the lower end of lever 160 pivoted on shaft 147. The upper end of lever 160 is connected to toggle links 134 by means of link 161 and its rearward 10 motion breaks the toggle and pulls crank 136 downwardly thereby removing lug 138 from restraining the descent of the clamp, Fig. 18. Nuts 162 are provided on the end of rod 159 in order to vary its effective length and 15 time of breaking of the toggle.

The clamp descends rapidly until it comes into contact with the pile of paper and the paper is further compressed by the pressure exerted by fingers 154 on fingers 155 by 20 means of the friction drive 144-145, link 150, crank 151 and shaft 152.

This preliminary descent of the clamp gives the operative a means of gauging the work to be cut. If the gauge is found to be 25 correct, he may operate the control lever to cause the knife to descend and also, before the actual cutting occurs, to cause more pressure to be applied to the clamps by the operation of the machine.

30 In order to enable the clamps to be raised from its lowest position, the following mechanism is provided: Parallel to each slide 130 and passing through abutments 131 and blocks 132 are rods 163 around each of 35 which is mounted a helical spring 164 the upper end of which presses against abutment 131. The lower ends of the springs contact washers 165 fastened in place on the rods by means of nuts. The rods are maintained 40 in their normal position, Fig. 20, by means of nuts 166, resting upon blocks 132. When treadle 141 is depressed, a member 167 is positioned under the end of each rod 163 and the downward movement of links 157 and 45 slides 130 will cause springs 164 to be compressed between the lowered abutments 131 and washers 165, for rods 163 will be held in elevated positions by reason of their contact with members 167.

50 When pressure on the foot treadle is eased off enough to break the contact between friction roll 144 and disk 145, the additional pressure that was exerted through link 150, crank 151 and shaft 152 is relieved, and the 55 stored energy in the springs 164 will operate to raise the clamp to its normal position thereby raising slides 130, links 157, and rotating cranks 156 and causing fingers 155 to engage fingers 154 to rock shaft 152 clockwise. This rotation of shaft 152 operates to move the lower end of lever 160 rearwardly through spring 159' on rod 159 and thereby cause link 161 to move forwardly and close toggle 137. Treadle 141 is 60 returned to its normal position by spring 141'

interposed between itself and forward tie-bar 3, Fig. 17.

Operation of one-piece clamp by the machine.

The above described preliminary clamping 70 operation of the paper is convenient when fine work is to be done, but ordinarily it will be sufficient to have the clamp operated by the machine during the paper cutting operation. 75

When the machine is operated to perform the cutting operation, the cones on shaft 19 and sleeve 21 are coupled and motion is communicated to shaft 24 through gears 22, 23, and 25. Gear 168, fast to shaft 24, will 80 be driven counterclockwise, and planetary gear 134' will be rotated thereby causing the straight links of toggle 134 to descend. At the same time, the forward end of triangular lever 135 will fall rapidly, since the high 85 part of cam 169 has been removed from under roller 170.

These combined movements lower the toggle to the position shown in Fig. 19, and thereby rotate crank 136 so as to terminate 90 the restraining effect of lug 138 on lug 139. Since the clamp is no longer held from descending, it will quickly come into contact with the surface of the pile of paper.

As in the case with my two-clamp modification hereinbefore described, it is desired 95 that the paper be firmly compressed to a desired maximum pressure before the knife starts to cut and in order to accomplish this I make use of the slip clutch illustrated in 100 Figs. 13, 14, 15, 16 and 21, the operation of which has been fully described.

Continued rotation of shafts 15 and 24 will cause the triangular lever plate 135 and planetary gear 134' to raise the clamp by 105 means of the straight toggle links 134 which act as a connecting rod between the planetary system and crank 136.

This restoring movement of the connecting rod 134, 134 causes link 161 to oscillate lever 160 slightly and such motion is permitted by the sliding connection between the lower end of lever 160 and rod 159. 110

Control of machine.

The operation of the knife may be controlled by the operative's lever 28 and cooperating mechanism already described or by the control mechanism illustrated in Figs. 21, 22, 23, 24 and 25. This mechanism comprises a circular disk 171 keyed for sliding motion on shaft 24 and having a grooved hub 172. A cross beam 173 supports bracket 174 which supports vertical shaft 175 to the lower end of which is fastened a yoke 176 120 having studs to engage the grooved hub 172. Arm 177 at the upper end of the shaft is connected to arm 178 by link 179 which is fastened to shaft 180, to the upper end of which is connected an arm 181. Pivoted connect- 125 130

ed with arm 181 is a cylinder 182 containing spring 183 the left end of which is fastened to the cylinder end. A piston rod 184 slides within the cylinder and is pivotally connected at its right end to arm 185 fastened to sleeve 186. Handle 187 is provided on the upper end of the sleeve for rotating the sleeve and rocking the sleeve and rod 188.

The inoperative or locked position of this mechanism is illustrated in Fig. 21 and lever rod 188 cannot be swung to the left before sleeve 186 is rotated counterclockwise to the position shown in Fig. 22. Rotating the handle 187 causes thumb 189 to kick latch 190 out of latching position where it is held by spring 191 when in locked position.

Handle 187 is then rotated to the right, Fig. 23, and the head of piston 184 contacts the right end of cylinder 183 and rotates shaft 180 and shaft 175 counterclockwise with the effect that disk 171 on shaft 24 is slid to the left by yoke 176. This moves it out of alignment with locking nose 192 of disk 193, which is secured to shaft 15, so that shaft 15 may rotate.

Lever rod 188 is then rocked to the left, Fig. 24, in which position spring 183 is compressed without any disturbance of the unlocked relation of the disks 171, 193, and latch 190 is cocked by thumb 189 so as to be operative to engage notch 190' when the lever bar is again returned to normal position. This leftward rocking motion of the lever rod and its hub 194 about its support will 35 rotate shaft 34 to the right, Fig. 21, through the instrumentality of link 195 and crank 196, fast to shaft 34. It will be remembered that the rotative position of shaft 34 controls the operation of the machine through 40 its connection with sliding shaft 35 by yoke 36 and collar 37. This sliding shaft carries the brake block 38, which, when moved to the right releases the hold of exterior brake-band 41 on the outer surface of the outer or driven friction cone 20. As this releasing operation is taking place, the inner friction cone is being slid to the right so as to engage the inner friction surface of the outer cone 20, and the continuously rotating power shaft 19, to which the inner cone is keyed, causes shafts 15 and 24 to be rotated with the accompanying operation of the clamp and knife in the manner already described.

At the completion of one cutting operation, that is, one drop and rise of the knife, the stopping device shown in Figs. 1, 6, 7, and 21 automatically acts to stop further operation of the machine and cause the knife to be held in its raised position. This stopping device consists of a disk 57, secured to shaft 15, and a cam finger 58 which causes the positive depression of arm 54 on shaft 34. Arm 54 is fixed to shaft 34 and the leftward motion, Fig. 21, of the shaft causes 60 the clutch members on shaft 19 and sleeve

21 to disengage as well as break the further operation of sleeve 21 as hereinbefore described. This leftward motion on shaft 34 pulls on link 195 through crank 196 and locks rod 188 and its hub 194 to their extreme right hand positions.

Prior to the stopping of the machine in this manner, the inclined flange 197 operates against the left side of disk 171 and cams the disk to the right from the position shown in Fig. 24 to the position shown in Fig. 21. This action rotates shaft 175 and shaft 180 clockwise, (Fig. 24) and causes the right end of cylinder 182 to draw piston 184 to the left with the attendant counterclockwise rotation of sleeve 186 and handle 187. In this position, latch 190 will engage notch 190' and hold the operative's lever in the inoperative or normal position, Fig. 21.

Immediately thereafter, the operation of the machine ceases and further operation is prevented by reason of the position of locking abutment 192 ready to contact disk 171 should shaft 15 attempt to rotate, Fig. 25. It is evident from the foregoing that it is impossible for the knife to fall when the shafts are locked by disks 171, 193 and that this locking mechanism is related with the clutch and brake as well as the operative's lever. For another cutting operation it is necessary to again operate the lever in the manner described, but I wish it to be understood that it is not necessary to provide the preliminary rotational caution motion for the use of these locking disks since they may be used in conjunction with the operative's lever 28 disclosed herein, and with like devices.

My invention is capable of a wide variation and relationship of parts without departure from the nature and principle thereof and I do not restrict myself unessentially in the foregoing or other particulars, but contemplate such alterations and modification within the scope of the appended claims as may be found to be advisable.

What I claim is:

1. In a paper cutting machine having a vertically movable knife and paper clamp, the combination of means for supporting the clamp in a raised position, a shaft for reciprocating the knife, means controlled by said shaft for permitting a rapid descent of the clamp ahead of said knife and into pressing engagement with the material to be cut, and other means operated by said shaft for transmitting to said clamp an additive pressure before the knife arrives opposite the clamp.

2. In a paper cutting machine having a vertically movable knife and paper clamp, the combination of a shaft having connections for reciprocating the knife, means for supporting the clamp in a raised position, means controlled by the shaft for removing

said clamp supporting means at the early part of the down stroke of the knife so as to permit said clamp to move into pressing engagement with the material to be cut, and other means for applying additive pressure to the clamp before the knife edge has arrived opposite the lower surface of the clamp.

3. In a paper cutting machine having a vertically movable knife and paper clamp, the combination of a shaft having connections for reciprocating the knife, means for supporting the clamp in a raised position, means controlled by the shaft for removing said clamp supporting means at the early part of the down stroke of the knife so as to permit said clamp to move into pressing engagement with the material to be cut and other means for maintaining pressure on said clamp during the cutting operation of the knife.

4. In a paper cutting machine having a vertically movable knife and paper clamp, the combination of means for actuating the knife, means for holding the clamp in raised position, automatic means for withdrawing said holding means to permit said clamp to descend, and other means for applying force to said clamp during the cutting operation of said knife.

5. In a paper cutting machine having a vertically movable knife and paper clamp, the combination of means for actuating the knife, means for holding the clamp in raised position, automatic means for releasing said holding means to permit said clamp to descend, other means for applying force to said clamp during the cutting operation of said knife, and means for actuating said holding means to raise said clamp after the cutting operation is completed.

6. In a paper cutting machine having a vertically movable knife and paper clamp, the combination of means for actuating the knife, means for holding the clamp in raised position, automatic means for withdrawing said holding means to permit said clamp to descend, other means for applying force to said clamp during the cutting operation of said knife, and means for actuating said holding means towards its normal position so that it will start to return the clamp after the knife has started its upward stroke.

7. In a paper cutting machine having a vertically movable knife and paper clamp, the combination of means for actuating the knife, means for holding the clamp in raised position, and planetary gearing for releasing said holding means to permit said clamp to descend ahead of said knife.

8. In a paper cutting machine having a vertically movable knife and paper clamp, the combination of means for actuating the knife, means for holding the clamp in raised position, and planetary gearing for with-

drawing said holding means to permit said clamp to descend, said planetary gearing being capable of lost motion to permit the return of said knife to its elevated position prior to the return of said clamp.

9. In a paper cutting machine, in combination with a knife, a clamp, a shaft for actuating said knife, means for supporting said clamp in a raised position, and means controlled by said shaft for releasing said clamp, said last named means being effective to release said clamp at the beginning of the knife descending stroke and to return it to normal position towards the end of the rising stroke of said knife.

10. In a paper cutting machine, in combination with a knife, a clamp, a shaft for actuating said knife, means controlled by the said shaft for controlling the operation of said clamp comprising a cam, a loose collar for raising said clamp, a planetary gear connected to said loose collar, a lever carrying said planetary gear and resting upon said cam, and a gear train intermediate said shaft and said planetary gear for rotating the latter to allow the loose collar to let fall and raise the clamp on each cycle of operation of the knife.

11. In a paper cutting machine, the combination of a knife, a clamp, a shaft directly connected with said knife, a second shaft directly connected with said clamp, means on said second shaft for holding said clamp in its raised position, and means intermediate said means and said first named shaft for controlling the fall and rise of said clamp, said last named means being controlled by said first named shaft.

12. In a paper cutting machine, the combination of a knife, a clamp, a shaft directly connected with said knife, a second shaft directly connected with said clamp, means on said second shaft for holding said clamp in its raised position, and means intermediate said means and said first named shaft comprising a planetary gear system controlled by said first named shaft for giving a variable rate of travel to the clamp.

13. In a paper cutting machine having a power actuated knife and a clamp, the combination of a shaft for actuating said knife, a second shaft for transmitting pressure to said clamp, a friction slip clutch mounted on said second shaft comprising a housing bearing a toothed ring, a plurality of contiguous disks alternately fixed to said housing and to said second shaft, a follower plate, a plurality of levers within said housing for pressing the follower plate against the disks, a collar for adjusting the position of said levers, and means intermediate said first named shaft and said toothed ring for rotating the housing.

14. In a paper cutting machine having a power actuated knife and a clamp, the com-

- 5 bination of a shaft for actuating said knife, a second shaft for transmitting pressure to said clamp, a friction slip clutch mounted on said second shaft comprising a housing bearing a toothed ring, a plurality of contiguous disks alternately fixed to said housing and to said second shaft, a follower plate, a plurality of levers within said housing for pressing the follower plate against the disks, 10 a collar for adjusting the position of said levers, means adjacent said housing having ratchets for engaging the teeth of said toothed ring, an eccentric on said first mentioned shaft, and a member actuated by said eccentric for controlling the engagement of said teeth and the rotation of said housing.
- 15 15. In a paper cutting machine, the combination of a paper clamp, means for supporting the clamp in a raised position, a constantly rotating drive means, means for releasing the clamp and applying pressure thereto, a manipulative means for rendering said last named means operative to be controlled by said drive means, and a slip connection between said drive means and said clamp releasing and pressure applying means.
- 20 16. In a paper cutting machine having a vertically movable knife, the combination of a paper clamp, a constantly rotating drive means, means for applying pressure to the clamp without effecting change in the position of the knife, manipulative means for rendering said last means operative, and a slip connection between said drive means and said pressure applying means.
- 25 17. In a paper cutting machine, the combination of a paper clamp, a shaft connected thereto, means coacting with said shaft for maintaining said clamp in a raised position, toggle links connected with said means, means for breaking said toggle to allow the clamp to move, a constantly rotating shaft, friction connections between said last named means and said rotating shaft, and means to render said friction connections effective for operating said toggle links to allow the clamp to move.
- 30 18. In a paper cutting machine, the combination of a paper clamp, a shaft connected thereto, means coacting with said shaft for maintaining said clamp in a raised position, toggle links connected with said means for breaking said toggle to allow the clamp to move, a constantly rotating shaft, means for connecting said last named means and said rotating shaft, and manipulative means to render said connecting means effective for operating said toggle to allow the clamp to move.
- 35 19. In a paper cutting machine, the combination of a paper clamp, a shaft connected thereto, means coacting with said shaft for maintaining said clamp in a raised position, toggle links connected with said means for breaking said toggle to allow the clamp to move and for moving said clamp, a constantly rotating shaft, slip connections between said last named means and said shaft, and a manipulative device for rendering said slip connections operative.
- 40 20. In a paper cutting machine having a reciprocating knife, the combination of an operation controlling shaft, means controlled by said shaft to cause the starting and stopping of the machine, a manipulative means to operate said shaft to control starting, a second shaft, a cam means on said second shaft, a member connected to said first shaft having a projection thereon for cooperative relation with said cam means to control stopping, and means controlled by said first shaft to lock the knife in its raised position when the machine is stopped.
- 45 21. In a paper cutting machine having a reciprocating knife, the combination of an operation controlling shaft, means controlled by said shaft to cause the starting and stopping of the machine, a manipulative means to operate said shaft to control starting, a second shaft, a cam means on said second shaft, a member connected to said first shaft having a projection thereon for cooperative relation with said cam means to control stopping, a locking disk on said second shaft, and a slid able disk adapted to be alined with said locking disk to prevent further operation of the machine.
- 50 22. In a paper cutting machine, the combination of locking means for preventing operation of the machine prior to the rocking of an operation controlling shaft, comprising two disks mounted on adjacent shafts and relatively movable, a nose on one of the disks for contacting the other of said disks to prevent rotation thereof, a yoke engaging the hub of said second disk, a lever rod rotatively supported, means intermediate said yoke and said lever rod for allowing said lever rod to move said yoke in a single direction, and a cam surface on said first named disk to move said yoke and connected disk in the opposite direction.
- 55 23. In a paper cutting machine, the combination of locking means for preventing operation of the machine prior to the rocking of an operation controlling shaft, comprising two disks mounted on adjacent shafts and relatively movable, a nose on one of the disks for contacting the periphery of the other of said disks, a yoke engaging the hub of said second disk, a lever rod pivotally supported, means connected with said lever rod for rocking said operation controlling shaft, rotative means supported by said lever rod, locking means for preventing a pivotal motion of said lever arm prior to a rotative motion of said rotative means, and means connected

with said rotative means for operating said yoke to move said second disk out of the path of the nose on said first named disk.

24. In a paper cutting machine, the combination of locking means for preventing operation of the machine prior to the rocking of an operation controlling shaft, comprising two disks mounted on adjacent shafts and relatively movable, a nose on one of the disks 10 for contacting the periphery of the other of said disks, a lever rod pivotally supported, means connected with said lever rod for rocking said operation controlling shaft, a handle on said lever rod, latching means requiring the rotation of said handle prior to a pivotal movement of said lever rod, and means intermediate said handle and said disks to move said disks out of alinement with each other.
- 20 25. In a paper cutting machine including an operation controlling mechanism comprising locking means to prevent operation of the machine and control mechanism for disengaging said locking means and causing 25 said machine to operate, the combination of two disks mounted on parallel shafts, a locking nose on one of said disks, means for moving said other disk out of alinement with said locking nose, a control lever rod, a handle on said lever rod for operating said last named means, and means controlled by the rotative position of said disks for returning said second mentioned disk to locking position.
- 35 26. In a paper cutting machine including an operation controlling mechanism comprising locking means to prevent operation of the machine and control mechanism for disengaging said locking means and causing 40 said machine to operate, the combination of two disks mounted on parallel shafts, a locking nose on one of said disks, an operation controlling lever rod, a handle rotatively mounted on said lever rod, means including 45 a one-way positive connection for moving said other disk by said handle out of locking relation, said means being ineffective when said lever rod is rocked to start the machine, and means to return said last named disk to locking position independent of said handle.
- 50 27. In a paper cutting machine, the combination of a knife actuating shaft, a disk on said shaft, a projection on said disk, means adapted to be positioned in the path of said 55 projection to prevent actuation of said shaft, manipulative means for causing the actuation of said shaft, and connections intermediate said last named means and said first named means to remove said first named 60 means from the path of said projection upon manipulation of said last named means.

28. In a paper cutting machine, the combination of a knife actuating shaft, a disk

on said shaft, a projection on said disk, 65 means adapted to be positioned in the path of said projection to prevent actuation of said shaft, and a cam surface on said disk for positioning said means in the path of said projection.

70 29. In a paper cutting machine, the combination of a knife actuating shaft, a disk on said shaft, a projection on said disk, means for locking said disk from rotation, 75 means adapted to be manipulated to remove said means from locking position, and a cam surface on said disk adapted to position said means in locking relation.

80 30. In a paper cutting machine, the combination of a knife, a clamp, means for supporting said clamp in a raised position, a shaft for reciprocating said knife, and means controlled by said shaft for permitting descent of said clamp ahead of said knife at a rate of travel greater than that of the knife, said means providing lost motion for delaying the return of said clamp.

85 31. In a paper cutting machine, the combination of a knife, a clamp, a shaft for reciprocating said knife, means for holding said clamp in elevated position, and a planetary device controlled by said shaft for actuating said means to permit the descent of said clamp ahead of said knife.

90 95 32. In a paper cutting machine, the combination of a knife, a clamp, a shaft for reciprocating said knife, means for holding said clamp in elevated position, a planetary device including a planetary gear, a toggle connecting said means and said planetary gear, a manipulative means, and means controlled by said manipulative means to open said toggle so as to remove said means from holding said clamp in elevated position.

100 105 33. The invention set forth in claim 32 in which said last named means is controlled by said manipulative means to open said toggle independent of the actuation of said knife.

110 34. In a paper cutting machine, the combination of a clamp, means to hold said clamp in elevated position, manipulative means, a constantly rotating power shaft, and means adapted to be connected to said power shaft to actuate said first named means upon the actuation of said manipulative means.

115 120 35. In a paper cutting machine, the combination of a clamp, means to hold said clamp in elevated position, a toggle connected to said means, a constantly rotating power shaft, a disk, connections between said disk and said toggle, and means to engage said disk to said power shaft to cause said toggle to open.

125 36. In a paper cutting machine, the combination of a clamp, means to hold said clamp in elevated position, manipulative means, a

- constantly rotating power shaft, means adapted to be connected to said power shaft to actuate said first named means to release said clamp, and means controlled by said last 5 named means to depress said clamp.
37. The invention set forth in claim 36 in which the means adapted to be connected to the power shaft is rendered operative by said manipulative means.
- 10 38. In a paper cutting machine, the combination of a knife, a clamp which is adapted to be actuated independent of said knife, means for supporting said clamp in an elevated position, means for releasing said 15 clamp from elevated position without effecting change in the position of said knife, a constantly rotating shaft, means to supply force to said clamp, and manipulative means to cause the operation of both of said means 20 by said constantly rotating shaft.
39. In a paper cutting machine, the combination of a knife, a clamp which is adapted to be actuated independent of said knife, means for supporting said clamp in an elevated position, means for releasing said 25 clamp from elevated position, a constantly rotating shaft, means to apply force to said clamp, manipulative means to cause the operation of said last mentioned means by associating the same with said rotating shaft, and means cooperating with said manipula- 30 tive means to return said clamp to elevated position.
40. The combination of a paper cutting machine in which a clamp may be operated 35 independent of the operation of a knife, means for supporting said clamp in an elevated position, means for allowing the clamp to descend, means for applying pressure to said clamp independent of the paper cutting 40 operation, manipulative means to control the operation of said means, and means to restore said clamp to elevated position.
41. The combination of a paper cutting machine in which a clamp may be operated 45 independent of the operation of a knife, means for allowing the clamp to descend, means for applying pressure to said clamp, a constantly rotating power shaft, friction 50 means driven by said power shaft, manipulative means for connecting said friction means so as to actuate both of said means, manipulative means for controlling the engaging relation of said friction means and said power shaft, and means for returning said clamp to 55 elevated position upon termination of engagement of said friction means with said power shaft.

In testimony whereof I hereto affix my signature.

TALBOT C. DEXTER.
